UNITED STATES PATENT OFFICE.

SAMUEL CLELAND DAVIDSON, OF BELFAST, IRELAND.

APPARATUS FOR COAGULATING RUBBER LATEX.

1,189,351.

Specification of Letters Patent.

Patented July 4, 1916.

Application filed October 14, 1915. Serial No. 55,856.

To all whom it may concern:

Be it known that I, SAMUEL CLELAND DAVIDSON, a subject of the King of Great Britain, residing at Sirocco Engineering Works, Belfast, Ireland, have invented certain new and useful Improvements in Apparatus for Coagulating Rubber Latex, of which the following is a specification.

This invention relates to apparatus whereby rubber is coagulated from the fluid latex by adding dilute acid or other coagulant thereto (hereinafter referred to as the "coagulant") and has for its object to provide improved apparatus for this purpose.

According to this invention the latex is caused to flow to and fro in an oscillating receptacle having an approximately central opening in its top adapted to permit the said coagulant to be gradually added during the oscillating movement of the receptacle. The to and fro motion of the oscillating receptacle, which is hereinafter referred to as the cradle, may be produced by swinging, oscillating, rocking, or reciprocating the cradle. The said "coagulant" may be added to the latex in the cradle during oscillation in any suitable manner, and the coagulated rubber and mother liquid may be discharged from the cradle in any convenient manner.

The cradle may be supported by links slung from above, or extending up from below, or it may slide horizontally upon a base, or in suitable guides, or it may be fitted to rock to and fro upon a pivot. When slung from the links, these may extend vertically upward from, at, or near the ends of the cradle to the support, or they may be convergent or divergent.

The cradle may be made to such a curvature in relation to the motion due to the method of supporting it, that the to and fro motion will cause the liquid to run along to the ends, and be then turned over by the curvature at the ends and fall about midway between the two ends on to the top of the liquid in the base of the cradle without spilling.

The accompanying drawings show one construction of apparatus made in accordance with this invention.

Figure 1 is a side elevation of the apparatus; Fig. 2 is an end elevation. Fig. 3 is a

plan; Figs. 4, 5 and 6 show details of the cradle to an enlarged scale; Figs. 7 and 8 are detail views slightly enlarged showing the cradle in the two opposite discharging positions.

Referring to the drawings *a* represents the swinging cradle which is of elongated form, with a gently curved base carried up in curvilinear, or semi-circular ends *a'*, giving the cradle a somewhat kidney shape in longitudinal section. The curved over ends *a'* are carried forward along the top about half-way between the ends and the center of the cradle, so as to leave a central open part *b* for pouring in the latex and adding the coagulating acid. The links *c* are attached to the cradle so as to permit its being swung to and fro by any suitable means. For example,—a crank or eccentric such as *f* with a suitable connecting rod *e* may be employed for this purpose.

A tank *l* is provided for the coagulant which in this case may be diluted coagulating acid. The said tank is located above the cradle *a*, and a suitable cock such as *n'* and preferably a measuring device is provided so that the coagulant in measured quantity can gradually flow or drip into the open top of the cradle *a* while the same is moving to and fro.

As regards the general construction of the apparatus illustrated, the swinging cradle *a* is carried on pins *b'* from the swinging links *c* which are in turn pivoted upon the pins *d*. A to and fro motion is imparted to the cradle through the connecting rod *e* by means of the crank *f* which may be rotated by means of the belt pulleys *g* or other suitable device. An alternative means of swinging the cradle by hand is provided by the handle *h*.

The cradle *a* and gear are carried upon the frame work *j* and *k* which can be made of wood, metal or other suitable material. The tank *l* for the coagulant is arranged on top of the frame work connected by a small pipe to an auxiliary tank *m*, which is so proportioned that it holds a known quantity of coagulant bearing a definite relation to the quantity of latex to be coagulated in the cradle.

n and *n'* represent two cocks interlocked,

and so arranged that only one can be open at a time, the other being closed, thus the bottom cock is closed, and the top one opened, allowing the coagulant to flow from the tank 5 *l* into the auxiliary tank *m*; then the top cock is closed and the bottom one opened, thus permitting the coagulant to fall or drip into the cradle, where it mixes with the latex during the coagulating process. An 10 air pipe *s* connects this auxiliary tank with the atmosphere at a higher level than the top of the upper or main supply tank.

The enlarged Figs. 4, 5 and 6 show that the particular cradle illustrated is made in 15 halves and bolted together on the vertical center line. Trunnion bearings are provided at the lower end of the links so that the cradle *a* may be turned over for emptying. Normally, the cradle is prevented 20 from turning over by spring catch *p*, but when this is disengaged, the cradle may be turned over to either side by means of the handle *h*.

As an illustration of how the machine is 25 worked, the latex to be coagulated is filled into the cradle to the extent of say about one-third its depth. The coagulant is then allowed to flow from the large tank *l* into the auxiliary tank *m*, a suitable fill of which 30 when diluted coagulant acid is employed is about half the bulk of the diluted coagulating acid, to that of the latex to be coagulated in the cradle. The supply is now cut off from the large tank, the tap of the auxiliary tank is opened, and the acid is allowed 35 to gently flow into the cradle while the cradle is being rocked to and fro at a sufficient speed to cause the fluid latex to rush from one end to the other of the cradle, and 40 which fluid when it turns over at each end should plunge into the central part of the cradle from the upper part of the curved over ends. Coagulation generally begins quickly, and, when completed the mother 45 liquor, will be found to be quite separate and apart from the coagulated rubber, and when this is the case the oscillation of the cradle is stopped, and the catch *p* is lifted and released; the cradle is now firstly turned over 50 to the side on which the screen *q* is mounted, see Fig. 7, whereupon the mother liquor flows on to one side of the deflecting chute *r*, from which it may be delivered into any 55 convenient receptacle, or sewer. Then the cradle is turned to the opposite side, see Fig. 8, and the coagulated rubber emptied on to the other side of said deflecting chute, and deposited into any suitable receptacle, which 60 may for example, consist of a tank of water either cold or heated even to the extent of boiling which helps to remove any remnant of the coagulant which may still be in the pores of the rubber. From this receptacle 65 the coagulated rubber may then be taken to whatever the next succeeding process

may be for manipulating said coagulated rubber.

What I claim as my invention and desire to secure by Letters Patent is:—

1. An apparatus for coagulating rubber 70 latex consisting of an elongated oscillating cradle in which the latex is caused to flow to and fro, said cradle having an opening in its top through which the coagulant may be gradually added to the latex during the oscillating movement of the cradle. 75

2. An apparatus for coagulating rubber latex consisting of an elongated oscillating cradle, in which the latex is caused to flow to and fro, said cradle having an opening in 80 its top approximately midway between the ends through which the coagulant may be gradually added to the latex during the oscillating movement of the cradle. 85

3. An apparatus for coagulating rubber 85 latex consisting of an elongated oscillating cradle, an approximately central opening in the top of said cradle, means for oscillating said cradle and means for supplying the coagulant gradually to the latex through the 90 said opening during the oscillating movement. 95

4. An apparatus for coagulating rubber latex consisting of an elongated oscillating cradle, an approximately central opening in 95 the top of said cradle, means for oscillating said cradle and a regulatable measuring device for adding the coagulant to the latex during the oscillating movement of the cradle. 100

5. An apparatus for coagulating rubber latex consisting of an elongated cradle, an approximately central opening in top of 105 said cradle, swinging link devices for supporting said cradle and means whereby said cradle may be swung on said links for the purpose of producing an oscillating movement of the cradle and means for supplying coagulant gradually to the latex through said central opening during the oscillating 110 movement. 115

6. An apparatus for coagulating rubber latex consisting of an elongated cradle, an approximately central opening in the top of 115 said cradle, swinging link devices for supporting said cradle, said links having a pivotal connection at ends of the cradle to permit of the swinging movement and a trunnion like connection on the longitudinal axis of the cradle for permitting the cradle to 120 be turned over to one side or the other for discharging the contents. 125

7. An apparatus for coagulating rubber latex consisting of an elongated cradle, an approximately central opening in top of 125 said cradle through which the coagulant may be added to the latex during the oscillating movement of the cradle, swinging link devices for supporting said cradle and means whereby said cradle may be swung 130

- on said links for the purpose of producing an oscillating movement of the cradle, a trunnion-like connection between the ends of the cradle and the swinging links whereby
- 5 the cradle may be turned over on one or both sides for the discharge of the contents, and means for locking the cradle in the vertical position.
8. An apparatus for coagulating rubber
- 10 latex consisting of an elongated oscillating cradle for receiving the latex, said cradle having an opening in its top through which the coagulant may be gradually added to the latex during the oscillating movement
- 15 of the cradle the ends of the cradle being made to such a curvature that the to and fro motion will cause the liquid to run along to the ends and be then turned over by the curved ends and fall on to the top of the
- 20 liquid in the base of the cradle without spilling.
9. An apparatus for coagulating rubber latex consisting of an elongated cradle, having an approximately central opening in
- 25 its top the ends of the cradle being made to such a curvature that the to and fro motion will cause the liquid to run along to the ends and be then turned over by the curved ends on to the top of the liquid in the base
- 30 of the cradle without spilling, swinging link devices for supporting said cradle and means whereby said cradle may be swung on said links for the purpose of producing an oscillating movement of the cradle.
- 35 10. An apparatus for coagulating rubber latex consisting of an elongated oscillating cradle in which the latex is caused to flow to and fro, said cradle having an opening in its top through which the coagulant
- 40 may be gradually added to the latex during the oscillating movement of the cradle, means for permitting the cradle to pivot on its longitudinal axis and means for locking the cradle in its position of use, a double
- 45 discharge chute beneath the cradle whereby the cradle may be turned to one side to discharge the mother liquor and on the other side to discharge the coagulated latex.
11. An apparatus for coagulating rubber
- 50 latex consisting of an elongated cradle, an approximately central opening in the top of said cradle, swinging link devices for supporting said cradle, and means whereby said cradle may be swung on said links for
- 55 the purpose of producing an oscillating movement of the cradle, a pivotal connection between the cradle and said links and a locking device for keeping the cradle in vertical
- 60 position while it is oscillated, a double discharge chute beneath the cradle

whereby the cradle may be turned to one side to discharge the mother liquor and on the other side to discharge the coagulated latex.

12. An apparatus for coagulating rubber

65 latex consisting of an elongated cradle, an approximately central opening in the top of said cradle, swinging link devices for supporting said cradle and permitting oscillating movement thereof, a rotary crank device and connecting rod for imparting oscillation to said cradle.

13. An apparatus for coagulating rubber latex consisting of an elongated cradle, an approximately central opening in the top

75 of said cradle, swinging link devices for supporting said cradle and permitting oscillating movement thereof, a rotary crank device and connecting rod for imparting oscillation to said cradle, a trunnion connection

80 between the ends of said cradle and the swinging links, means for locking the cradle in the vertical position and for permitting the cradle when released to be turned over to one side or the other for discharging the

85 contents.

14. An apparatus for coagulating rubber latex consisting of an elongated cradle, an approximately central opening in the top of

90 said cradle, swinging link devices for supporting said cradle, a rotary crank device and connecting rod for imparting oscillation to said cradle, a pivotal connection between the cradle and said links and a locking device for keeping the cradle in vertical

95 position while it is oscillated, a double discharge chute beneath the cradle whereby the cradle may be turned to one side to discharge the mother liquor and on the other side to discharge the coagulated latex.

15. An apparatus for coagulating rubber latex comprising a cradle having a to and fro motion, and means in said cradle for deflecting the latex toward the middle of the cradle at the ends of the to and fro

105 movements of the cradle.

16. An apparatus for coagulating rubber latex comprising a cradle having a to and fro motion, and means in said cradle for deflecting the latex toward the middle of the

110 cradle at the ends, said cradle being pivotally mounted and being adapted to be turned on its side for emptying purposes.

In witness whereof, I have hereunto signed my name in the presence of two subscribing witnesses.
